GRINDING ROLL

Alfred E. Hamilton, Pittsburgh, Pa.

Application March 23, 1946, Serial No. 656,724

5 Claims. (Cl. 51—192)

1

My invention relates to rolls for grinding and polishing wood, metal, and other materials, including strips and sheets, and more particularly to rolls of the pneumatic type wherein air is maintained under desired predetermined pressures to provide for desired degrees of grinding pressure, but certain features of the invention are applicable also to rolls of yieldable or compressible material such as sponge rubber.

In making of surfacing drums of the pneumatic type, it has heretofore been common practice to incorporate therein reinforcing or restraining strips at axially-spaced points intermediate the ends of the drum, along circumferential lines, to support the intermediate areas of the drum against too great radial stress or displacement under the internal air pressure or centrifugal force, since these intermediate areas do not have the benefit of the support afforded at the ends of the drum by their walls. The result is that there are more or less defined circumferential areas some of which are, in effect, harder than the others, which tends to give a pattern or streak.

In some instances, abrasive-containing sleeves have been placed on the drums while the drums are under no internal air pressure, but slight manufacturing differences in the diameters of the sleeves sometimes give difficulty, because of danger of rupturing the sleeve when air, under working pressures, is introduced into the drums. They frequently fail at the seam or lap where the ends of the strip are glued together to form the sleeve.

While helically-wound abrasive strips have been used on pneumatic drums, with their ends clamped at the ends of the roll, and they have been more satisfactory than the sleeves, in that they are readily adaptable to rolls of varying diameter, they still have not overcome the necessity for employing the circular reinforcing strips intermediate the ends of the drum. Furthermore, they have a tendency to distort the drum on diagonal lines when air pressure is introduced into the drum.

One object of my invention is to provide surfacing rolls of the pneumatic or yieldable type wherein the advantages of the diagonally-wound strips over the abrasive sleeves are retained and certain other advantages secured that are not present with the use of the ordinary spirally-wound drum. Among these advantages are:

(a) Strengthening the drum against radial displacement under centrifugal or pneumatic forces while avoiding danger of a "pattern" on the surfaced material, such as results from the use of

circumferential stiffening or restraining elements.

(b) Avoidance of or compensation for distortion stresses diagonally of the drum.

(c) Provision for "chip clearance" and disposal of the powder-like fines resulting from grinding.

(d) Provision for relatively stiffer and softer areas at the periphery of the drum, which will render the drum more adaptable to non-planular surfaces on which the drum operates, but wherein the stiffer and more flexible areas, respectively, alternate at any given zone circumferentially of the drum.

Figure 1 is a face view of a grinding roll that embodies my invention, and Fig. 2 is a fragmentary, enlarged sectional view of a portion of the structure of Fig. 1.

It will be understood that either a single roll may be employed, for surfacing one side of a sheet or strip, or that a pair of the rolls can be used in opposed relation, to surface both sides of a sheet simultaneously. Only so much of the invention is shown as is required for an understanding of the invention. A pair of the rolls

may be mounted in the manner shown for example in my Patent 2,368,760 and fluid pressure supplied to the pneumatic drums on the rolls in the manner shown in my said patent.

A shaft 4 is mounted in suitable bearings and carries a pulley 5 by which the shaft will be driven from any suitable source of power. A hub 6 is secured to the shaft and carries a pneumatic drum 7 which is of flexible material such as rubber and contains an annular chamber 8 to which air under pressure may be supplied and maintained

through a swivel coupling 9, a conduit 10 in the shaft 4, and a pipe 11 during rotation of the drum, as described in my said patent. Strips 12 of tough paper or other flexible material are helically wrapped around the drum in one direction, the successive helical turns being spaced apart a distance of perhaps one inch. Abrasive strips 13, which may be approximately 4 inches wide as in the drawing, or other suitable widths, are helically wrapped around the first-mentioned strips and the drums in the opposite direction so that the turns of the outer abrasive strips cross the turns of the strips 12 on diagonal lines. This leaves the diamond-shaped spaces or pockets

14 adjacent to the points of crossing, of a depth equal to the thickness of the two layers of strips. The ends of the strips, or at least of the abrasive strips 13, are secured in any suitable manner to maintain them in wrapped condition, but I here show them turned backwardly and tucked in be-

tween the periphery of the hub 6 and the inner surface of the drum 8, as shown at 15 in Fig. 2. The air pressure within the drum 7 will expand the drum, thus pinching or gripping the back-turned ends of these strips and holding them in place. This holding effect is increased by reason of the fact that the abrasive grains on the surfaces of the abrasive strips, at the back-turned ends, are held with a biting force against the periphery of the hub. The strip ends at the other end of the drum will be held in like manner.

The helically-wound strips 12 serve to restrain the drum against radial distortion either under centrifugal force or internal air pressure, and being along diagonal or helical lines, there are no circumferential zones of varying degrees of resistance to deflection. Furthermore, these strips 12 being wrapped oppositely to the abrasive strips 13 counteract the tendency of the strips 13 to distort the drum along diagonal lines when under working tension.

The diamond-shaped spaces or pockets at 14, as well as the spaces between adjacent edges of the helically-wound strips 13, serve as spaces to receive the grindings from the work piece as well as the dust from worn abrasive grains. Any grindings that accumulate therein while passing over the work will be thrown clear of the rolls as they are carried out of contact with the surface of the work.

Another feature of advantage resides in the fact that the abrasive strips, under working pressures, will be more flexible at points where they are in proximity to the edges of the underlying strips 12, such as at 16x, than at the zones 17 intermediate such points 16, since the strips 12 will offer greater resistance to deflection of the strips 13 at the zones 17 than they will at the edges of the strips 12. This not only enables the roll to operate more uniformly on surfaces that are not completely planar, but gives, in effect, a two-grade grinding action, since at the more resistant areas 17, there will be greater grinding pressure than at the more yieldable areas 16x.

It will be understood that the various advantages resulting from the use of the oppositely-wrapped strips 12 and 13, except for the matter of clip clearance, will be present also if these strips are closely wrapped on the drum instead of having the adjacent edges of each set of strips spaced apart as in Fig. 1.

The drum is held against slipping axially of the hub, when inflated, by the annular depression at 8 in the hub, into which the rubber is swelled.

I claim as my invention:

1. A grinding roll comprising a hub, a flexibly-walled pneumatic drum on the hub, a restraining strip wound helically around the periphery of the drum, with a plurality of turns, an abrasive strip wound helically around the restraining strip and the drum, with a plurality of turns and in a direction opposite to the restraining strip, and means

for securing the ends of the strips against displacement.

5 2. A grinding roll comprising a hub, a flexibly-walled pneumatic drum on the hub, a restraining strip wound helically around the periphery of the drum, with a plurality of turns, an abrasive strip wound helically around the restraining strip and the drum, with a plurality of turns and in a direction opposite to the restraining strip, and means for securing the ends of the strips against displacement, the convolutions of each of the strips being spaced apart a substantial distance.

10 3. A grinding roll that is radially yieldable to a substantial depth in its peripheral portion, restraining elements having a plurality of turns disposed on generally helical lines adjacent to the periphery of the roll and arranged to resist radial expansion thereof, and an abrasive strip having a plurality of turns extending around the peripheral surface of the roll on helical lines in a direction approximately opposite to the first-named lines.

15 4. A grinding roll that is radially yieldable to a substantial depth in its peripheral portion, restraining elements having a plurality of turns disposed on generally helical lines adjacent to the periphery of the roll and arranged to resist radial expansion thereof, and an abrasive strip having a plurality of turns extending around the peripheral surface of the roll on helical lines in a direction approximately opposite to the first-named lines, the convolutions of the said elements being spaced apart axially of the roll and the convolutions of the abrasive strip being spaced apart axially of the roll, the said spacing being less than one-half the width of the abrasive strips.

20 5. A grinding roll that is radially yieldable to a substantial depth in its peripheral portion, a restraining strip helically wound in a plurality of turns on the peripheral surface of the roll, and an abrasive strip helically wound in a plurality of turns around the restraining strip in the opposite direction, the convolutions of the restraining strip being spaced apart axially of the roll to thereby provide different degrees of resistance to grinding pressures imposed upon various areas of the abrasive strip.
